WRENCH

Jason N. Horner, Los Angeles, Calif., assignor to
Crane Co., Chicago, Ill., a corporation of Illinois

Application May 28, 1935, Serial No. 23,871

4 Claims. (Cl. 81—99)

My invention is directed toward a particular type of wrench which is suitable for the gripping and handling of pipe or similar round or tubular material, as for example, in connection with certain operations of fabrication, such as bending, flanging, threading, and the like.

It is well known that in the matter of providing for the safe, quick and convenient handling of relatively heavy, large diameter pipe, that when the latter is being threaded, for example, or otherwise fabricated, a positive and effective means for gripping the same is an absolute necessity. This is especially applicable for such work where the size and weight of the material requires that it should be done upon a machine in cooperation with a balanced crane running on an overhead track or trestle or similar supporting means.

Heretofore it has been found that the handling of heavy and large size diameter pipe has been extremely cumbersome and quite frequently very unsafe because of the inability of gripping the pipe in an effective manner without damage thereto or to otherwise avoid slipping. At the same time, the grip while it must necessarily be positive, it should preferably be such as to be accomplished relatively quickly and with a minimum of effort, in addition to being readily releasable by the user when it is subsequently required.

Therefore, it is one of the important objects of this invention to provide a wrench which will provide for such positive gripping and likewise will permit quick and convenient removability when the use of the wrench is no longer desired, as for example, after the pipe being handled has been properly positioned in a pipe threading machine or is ready for the subsequent fabrication which may follow.

Another important object is to provide in a wrench of this character for a positive grip which does not flatten or distort the pipe, and by means of a counterbalanced supporting means lessens the likelihood of an accident.

Another important object of this invention is to provide for a wrench in which the jaws may be readily removable, adjustable and/or renewable to suit the conditions of use. It is a further object to provide for a wrench which will have a body or fixed jaw that is readily interchangeable with numerous and variable sizes of jaws, depending upon the size and weight of pipe to be handled.

Another equally important object is to provide for a relatively heavy wrench which may be easily supported from above by means of a running

crane or similar counterbalanced support, and further in which the wrench may be conveniently guided by means of an extension or handle to the position desired with respect to the machine to be used for ultimate fabrication. Likewise, such handle may be designed specially or lengthened to provide the necessary balancing of the complete wrench assembly so as to maintain the latter in a preferably horizontal position or in such angle of inclination as may best suit its subsequent usage.

Another object is to provide for a wrench in which the pipe, or similar article to be handled, after being placed within position in the cradle of the body may be quickly and securely clamped by a cam or similar actuating means so as to be firmly and positively locked in position within the opposing jaws.

Another important object is to provide for a wrench in which ready adjustability is accomplished by quickly removable means without the requirement of excessive strength and effort on the part of the operator, and in which the principal gripping load is supported by positive means independent of the said adjustment.

Other objects and advantages of this invention will become apparent upon reading the following description in connection with the drawing, in which

Fig. 1 is an exterior side view showing a mounting of the wrench in connection with a weighted or counterbalanced supporting means in which the latter is mounted upon a track or trestle and preferably suspended from overhead.

Fig. 2 is an enlarged fragmentary exterior view in partial section showing in more detail the assembly and operation of the combination comprising the head, jaws, locking cam, case, lever, etc.

Fig. 3 is a sectional assembly view taken on the line 3—3 of Fig. 2.

Directing attention to Fig. 2, the wrench head gripping means comprises a body 1 suitably constructed for pivotal assembly with a jaw 2. It is preferable, although obviously not absolutely essential, that the body should be provided with a guiding and balancing handle 3 suitably attached thereto by the bolts 4 and positioned within the groove or channel 10. The body 1 is preferably provided with an overhead support attaching means, such as an eye bolt 5, adaptable for connection to a cable or cord 6 mounted in peripheral relation upon a pulley 7 in combination with a suspended counterbalanced weight 8, the pulley 7 being rotatably mounted upon the usual

overhead track 9 by means of the conventional trolley wheel 11, all of which is more clearly shown in the upper portion of Fig. 1.

Reverting again to Fig. 2, the jaw 2 is provided with a preferably integral extension shank 12 which for a portion of its length is of a divided or bifurcated construction with ends connected as illustrated. By means of the pin 13 the bifurcated shank 12 is pivotally connected and preferably placed in adjustable relation to the depending shank portion 14, the latter extending within the space provided by the divided shank portion as shown more clearly in Fig. 3. The pin 13 is preferably provided with a convenient looping ring 13a for purpose of quick withdrawal from the hole 13b as well as to facilitate quick replacement where necessary in order to properly adjust the jaws 2 for the diameter of pipe required. As shown in Fig. 2 there may be provided a number of holes 13b and the sizes thereof also may vary depending respectively upon the number of gripping adjustments desired and also upon the weight and bulk of the material to be handled.

The body 1 is provided with the customary positioning means 15 forming a cradle or V-portion therein having a lower portion serrated as at 16 in order to better grip the pipe "A" and also restrain rotation thereof. Similarly, the engaging extension 17 of the jaw 2 is provided with a serrated face 18 for the same purpose. The respective serrated faces 16 and 18 may preferably be inserts formed of a hardened renewable metal, and suited to comply with the conditions of use. Of course, the jaws may be of any other desired form in order to conveniently handle special shaped material.

For the purpose of providing a degree of gripping flexibility within the jaw 2, a channel shaped portion or locking case 19 is provided with positive engagement with the lower end of the extension 16 by means of the bolts 21, the pin 13 serving as a pivot in which the weight of the jaw is supported by the springs 21a. The tension of the latter is therefore adjustable depending upon the degree of flexibility desired in locking the cam hereinafter described in the gripping position, considering the weight of piping or material to be handled, and also the avoidance of flattening the pipe.

In the foregoing paragraph, for convenience of reference, the member 19 has been referred to as a locking case. Obviously, this member need not necessarily take the case form disclosed, but may be modified considerably without departing from the function intended, that is, serving as a flexible or resilient stop or rest for the movable jaw 2.

At this point, it seems desirable that attention be particularly directed to a very essential element of my invention. Reverting to Fig. 2, the locking case 19 which, as previously mentioned, is preferably made of a channel cross-section, is provided at the end portion opposite to that in which it is attached to the end portion 14, with transversely positioned journaling means 22a which, as shown in Fig. 3, extend rotatably through both vertical walls forming the channel of the locking case 19. The journalled shaft 22a is provided for purpose of rotation with the extension handle 22 at right angles to the said shaft and preferably integral therewith, thus forming a locking lever for the purpose herein-after described.

A preferably circular locking cam 23 positioned between the walls of the channelled locking case 19, is mounted upon the pin 22a and attached eccentrically in non-rotatable relation therewith. It will thus be apparent that with the locking lever 22 in the position shown in the dotted lines upon turning the same in a clockwise direction of rotation, the eccentrically drilled locking cam will likewise be rotated thus taking the position shown in dotted lines. Such movement by the cam forces the jaw 2 to take the position shown in dotted lines and gripping the pipe firmly as indicated, the pin 13 serving as a pivot upon which the jaw 2 is centered in its upward arcuate movement.

It is obvious that the amount of displacement of the jaw 2 will of course depend upon the amount of eccentricity resorted to in fixedly attaching the journaling pin 22a to the locking cam 23. It is thus apparent that by the exercise of only a slight amount of effort a relatively great lifting and gripping load may be exerted in holding the pipe "A" in the position required.

It is further evident that I have accomplished quick, convenient and positive means for maintaining a heavy wrench in locked relation about cylindrical or tubular material, with a provision for quickly releasing the jaws when use of the wrench is no longer necessary. Obviously, this novel construction aids greatly in accomplishing convenience and celerity in performing the necessary operations upon the material to be handled.

Thus, assuming that it is now necessary to operate the same, the wrench is lifted and guided to the proper level by means of the counterbalance support 8, the wrench head is placed about the pipe and held in desired position by the guiding handle 3 so that the locking cam with the assistance of one hand of the operator upon the lever 22 may then be turned so as to rotate against the underside of the jaw 2, thus elevating the latter and obtaining a positive grip but avoiding excessive pressure which might otherwise flatten the outer contour of the pipe, and in addition by means of the counterbalanced support arrangement, the chance for accidents occurring is thus materially minimized.

To those skilled in this art, it is of course plain that modifications may be made in the details of construction, arrangement and mere matters of form without departing from the spirit of the invention, which is not limited to such matters or otherwise than the prior art and the appended claims may require.

I claim:

1. In a wrench of the class described comprising a handle having a fixed jaw, an extension from the said fixed jaw, a movable jaw pivotally connected to the said fixed jaw at the said extension, a locking case resiliently attached to the said extension, rotatable displacing means mounted upon said locking case and engaging the said movable jaw whereby upon rotation of the said means the said movable jaw is arcuately moved so as to close the said jaw upon an article being gripped between the said jaws.

2. In a wrench of the class described comprising a handle having a fixed jaw, a movable jaw, a lower depending extension from the said fixed jaw for pivotally supporting the said movable jaw, a locking case resiliently attached to the said extension, eccentrically mounted means upon said locking case and engaging the said movable jaw whereby upon actuation of the said mounted means the said movable jaw is displaced so as

to close the said jaw resiliently upon the article being gripped.

3. In a wrench of the class described comprising a handle having a fixed jaw, a movable jaw 5 pivotally supported upon a lower depending extension from the said fixed jaw, a locking case resiliently attached adjustably to the said extension, eccentric means upon said locking case and engaging the said movable jaw whereby upon 10 actuation of the said eccentric means the said movable jaw is arcuately displaced so as to close the said jaw resiliently upon an article being gripped between the said jaws.

4. In a wrench of the class described compris-

ing a handle having a fixed jaw, a movable L-shaped jaw having a plurality of openings in its shank for selective connection to a lower depending extension from the said fixed jaw, a pin passing respectively through one of said openings 5 and a complementary opening in said extension, a locking case resiliently attached to the said extension, displacement means mounted upon said locking case and engaging the said movable jaw whereby upon actuation of the said displacement means the said movable jaw is arcuately moved so as to close the said jaw upon an article being gripped. 10

JASON N. HORNER.
